UNITED STATES PATENT OFFICE

153,689

DESIGN FOR A LAMP OR SIMILAR ARTICLE

Alice Mason Johnson, Long Island City, N. Y.

Application June 19, 1948, Serial No. 147,090

Term of patent 3½ years

(Cl. D48—20)

To all whom it may concern:

Be it known that I, Alice Mason Johnson, a citizen of the United States of America, residing in Long Island City, county of Queens, and State of New York, have invented a new, original, and ornamental Design for a Lamp or Similar Article, of which the following is a specification, reference being had to the accompanying drawing, forming part thereof.

The figure on the drawing is a perspective view of a lamp or similar article showing my new design.

I claim:

The ornamental design for a lamp or similar article, substantially as shown.

ALICE MASON JOHNSON.
